WELT SUPPORT

Joseph Amico, Rochester, N. Y., assignor to Frank Keiper, Rochester, N. Y.

Application December 29, 1938, Serial No. 248,223

13 Claims. (Cl. 12—103)

Heretofore shoes have been regularly made with a welt attached to the upper, to which the sole of the shoe in the first manufacture of the shoe is attached by sewing, or to which a half-sole is attached by sewing in the repair of the shoe. It is now a common practice to attach the sole to the new shoe, or the half sole to an old shoe, by fastening thereon with cement. In such cases the sole or half sole is not sewed to the welt, but is cemented thereto. In such cases because the welt overhangs the last it will not be firmly supported thereby and extra support is needed therefor while the sole or half-sole is being attached thereto by cement under pressure.

The object of this invention is to provide a support for the welt of the shoe, so as to prevent it from yielding while the sole or half-sole is being fastened thereto by cementing under pressure.

Another object of the invention is to provide a support that can be quickly adjusted to a great variety of sizes and shapes of shoes.

Another object of the invention is to provide adjustment by which the welt support will be held firmly in place on the shoe and will give adequate support to the welt under pressure.

These and other objects of the invention will be illustrated in the drawings, described in the specification, and pointed out in the claims at the end thereof.

In the drawings:

Figure 1 is a bottom plan view of a small size shoe such as is worn by women and children, with the welt support in place thereon.

Figure 2 is a side elevation of the shoe and welt support shown in Figure 1.

Figure 2A is an elevation of the yoke of the welt support.

Figure 3 is an enlarged detail view of an extension of the welt support shown in Figures 1 and 2, looking at it from below.

Figure 4 is an enlarged end elevation of the detail shown in Figure 3.

Figure 5 is an enlarged view of the right hand portion of the welt support shown in Figure 1, looking at it from above.

Figure 6 is an end elevation of the yoke shown in Figure 5.

Figure 7 is a bottom plan view of a man's shoe with a welt support thereon embodying modifications from the welt support shown in Figure 1.

Figure 8 is a side elevation of the shoe and the welt support shown in Figure 7.

Figure 9 is an enlarged view of the forward portion of the welt support shown in side elevation in Figure 8, looking at it from the top.

Figure 10 is a sectional elevation through the welt support, the section being taken on the line 10x—10x of Figure 9.

Figure 11 shows a modified form of the support for the welt of a man's shoe, although it is obvious that this could be adapted to support the welt of a woman's shoe as well, looking at it from the bottom.

Figure 12 is a side elevation of the shoe and the welt support therefor that is shown in Figure 11.

Figure 13 is a section on the line 13x—13x of Figure 12.

Figure 14 is a detail view of the yoke and a portion of the shaft for drawing tight the cable.

20 In the drawings like reference numerals indicate like parts.

As above stated, it is common practice to attach soles or half-soles to shoes by cement, and where the shoe is provided with a welt some extra support is needed for the welt to hold it up under the pressure that is placed on the sole while it is being attached to the shoe in the cementing process. For this purpose I provide special forms of welt supports which will now be described as follows:

The welt support shown in Figure 1 comprises a yoke 1, Fig. 2A, having bifurcated ends 2 and 3, and 4 and 5, arranged in pairs, extending laterally therefrom and having brackets 6 and 7 extending upwardly therefrom. It also has a threaded opening 8 located centrally therein. Between the bifurcated ends 2 and 3 is pivoted the arm 9, and between the bifurcated ends 4 and 5 is pivoted the arm 10. Each of these arms 40 comprises a long extension 9A and 10A on one side of the pivot, and a short extension 9B and 10B on the other side of the pivot.

Threaded into the opening 8 is a stud 11, on which is mounted to slide a block 12. Between the block 12 and the yoke 1 is provided a helical compression spring 13. Threaded on the stud is a wing nut 14 by which the block 12 may be moved forward toward the yoke 1, the spring 13 being compressed between the two parts as they are drawn together. The ends of the block 12 are grooved, and in the grooves engage the short arms 9B and 10B. The inner edges of these arms are cam-shaped so that they react in the grooved ends of the block 12 and are spread thereby as the block advances. This, in turn, causes the

long ends 9A and 10A of the arms to be drawn together toward the shoe. On the long ends 9A and 10A of the arms is pivotally mounted extensions 16 and 17 which are adapted to engage in the groove between the welt and the upper of the shoe, and as the wing nut 14 is screwed forward it presses these extensions firmly in place, so that they act as a support for the welt while the last is in the shoe. In both the extensions 16 and 17 are provided holes. Through the hole in the extensions 16 the end of the cable 18 is passed and is fastened in place therein by a knot 19. This cable passes around the toe of the shoe and rests in the groove between the welt and the upper. It passes through a similar hole in the extension 17 and is drawn tight around the toe of the shoe by a mechanism that will now be described.

Mounted to turn in the brackets 6 and 7 is a shaft 20 having a wing head 21 fastened on the end thereof. The bracket 7 has its outer face grooved with grooves 22 as shown in Figure 6. On the outer end of the shaft 20 is provided a pin 23 which engages in one or the other pairs of these grooves. On the shaft 20 is provided a washer or collar 24, held in place by a pin 25. Between this washer and the bracket 7 is placed a helical spring 26 which normally moves the shaft 20 down, as shown in Figure 5, and holds the pin 23 in engagement with the one or the other pair of grooves as shown in Figure 6. The cable 18 passes through a hole 18A in the shaft 20, and by turning the shaft 20 the cable is wound up thereon and is drawn tight into the groove between the welt and the upper of the shoe. The cable is held in tension by the shaft, and the shaft is held against turning in the reverse direction by the engagement between the pin 23 and the grooves 22.

In regular operation a last is preferably used such as is shown in a companion application Serial No. 240,085, filed November 23, 1938. This last, or any equivalent last, is inserted in the shoe and the welt support is then applied to the shoe, first by turning the wing nut 14 so as to bring the extensions properly into engagement with the shoe, and then the cable is adjusted to the shoe, and the shaft 20 is turned so as to put it under tension. In this way the welt is firmly supported from the last within the shoe so that it will not yield under considerable pressure.

The shoe shown in Figures 1 and 2 is a so-called lady's shoe with a high heel, but it will be understood that this support can also be used on children's shoes, or ladies' shoes provided with low heels.

In Figures 7 and 8 I have shown the welt support applied to a man's shoe. In these figures the parts at the right of the welt support are all substantially the same as those shown in Figures 1, 2 and 5, the only difference being in the fact that the shaft 20 is preferably longer in a welt support used on a man's shoe than would be used in a welt support for a lady's shoe.

The long ends 9c and 10c are different from each other and are somewhat differently shaped from the arms 9A and 10A shown in Figure 1. This is due to the fact that the men's shoes are of greater width than ladies' shoes and they are made with a deeper curve on the inside of the arch of the foot than is found on the ladies' shoe. It is also true that while the welt support shown in Figure 1 can be used on either a right or a left shoe of the same pair, the welt support

shown in Figure 7 must be specially made for each of the right and left shoe of the pair. The one shown in Figure 7 is the welt support used on the left shoe of the pair, it being understood that the welt support for the right shoe of the pair will be merely the reverse of the support shown in Figure 7 and being made symmetrical therewith.

On the outer end of the arm 9c is pivotally mounted an extension 30 and rearwardly therefrom is also pivotally mounted an extension 31. On the outer end of the long arm 10c is pivotally mounted extensions 32 and 33 corresponding to the extensions 30 and 31. These extensions swing free on the arms and engage in the groove between the welt and the upper and adjust themselves thereto as the arms are drawn together, as above explained.

Fastened to the extension 30 is provided a cable 34 similar to the cable 18 above described, which passes around the sole of the shoe and through a hole in the extension 32. This cable then extends rearwardly and engages with the shaft 20, and is drawn tight around the toe of the shoe in the groove between the welt and the upper by turning the shaft 20, so that the welt is firmly supported thereby in the same manner as has been described in connection with the support used on the lady's shoe.

The extension 32 is shown in cross section in Figure 10, it being understood that all of these extensions 30, 31, 32 and 33 are wedge-shaped at the lower edge, as shown in Figure 10, so that they will project into and engage between the welt and the upper and will communicate the support of the last firmly to the welt.

In Figures 11, 12, 13 and 14 I have shown a modified form of the support for the welt of a man's shoe, although it is obvious that this can be adapted to support the welt of a lady's shoe as well. In this modified form 40 indicates the yoke on which the two arms 41 and 42 are pivoted, which arms have the short extensions 41A and 42A on one side of the yoke. The arms are drawn together by forcing the block 43 between the extensions 41A and 42B by means of the wing nut 44 as heretofore described in connection with Figures 1, 5, 7 et cetera.

On the outer ends of the long arms 41 and 42 is pivoted eveners 45 and 46. On each of these eveners is pivoted extensions 45A, 45B, 46A, and 46B. These extensions are adapted to engage between the upper and the welt of the shoe, so as to support the welt from the evener and the last within the shoe.

Mounted to turn in the yoke 40 is the shaft 47 having the handle 48 on the end thereof by which it can be turned. Between the brackets 6 and 7 on the yoke is provided a spring 26, which surrounds the shaft 47. On this shaft is a washer or collar 24 against which the spring presses. This collar is held against one-way movement on the shaft by the pin 25, so that the expansion of the spring pushes the shaft 47 down in Figure 14. In the bracket 7 is provided four grooves, similar to those shown in Figure 6 on the bracket 6, in which the pin 25 can engage and by which engagement the shaft is held against turning in any one of four positions in which it may be placed.

At 49 is provided a hole through which one end of the cable 18 passes. The other end of the cable is attached to one of the extensions, as indicated at 50 in Figure 11. This cable passes around the sole of the shoe between the welt and

the upper and through a hole in the extension 45A, so that the welt is directly supported from the upper, which in turn is held firm by the last which is inside of the shoe. This cable is drawn tight by turning the shaft 47. When the cable is drawn sufficiently tight, the spring 26 will expand and force the pin 25 into one of the slots and thus lock the shaft against reverse movement.

I claim:

1. In a support for the welt of a shoe the combination of a yoke, an arm pivotally mounted on each side of said yoke, extensions on the forward ends of said arms, said extensions being adapted to engage between the welt and the upper of the shoe for the purpose of supporting the welt from the upper, means extending rearwardly from the heel of the shoe for drawing said arms and extensions toward each other on opposite sides of the shoe, a cable attached to an extension on one side of the shoe said cable being adapted to pass around the toe of the shoe nesting in the groove between the upper and the welt, a guide opening in the corresponding extension on the opposite side of the shoe through which said cable is adapted to pass, and means for drawing said cable tight around the toe of the shoe so that the welt will be supported thereby from the upper of the shoe.

2. In a support for the welt of a shoe the combination of a yoke, an arm pivotally mounted on each side of said yoke, an extension pivoted on each arm adapted to engage between the welt and the upper of the shoe for the purpose of supporting the welt from the upper, means extending rearwardly from the heel of the shoe and slightly above the heel for drawing said arms and extensions toward each other on the opposite sides of the shoe, a cable attached at one end to an extension on one side of the shoe said cable being adapted to pass around the toe of the shoe nesting in the groove between the upper and the welt, a guide opening in the corresponding extension on the opposite side of the shoe through which said cable is adapted to pass, and a shaft mounted on said yoke to which the other end of said cable is attached, said shaft being adapted to be rotated for the purpose of drawing said cable tight around the toe of the shoe.

3. In a support for the welt of a shoe, the combination of means adapted to engage between the welt and the upper of the shoe from the outside of the shoe on the sides of the shoe, a cable passing around the toe of the shoe adapted to engage between the upper and the welt on the outside of the shoe, said cable being supported by said supporting means and cooperating therewith to support the welt from the upper of the shoe, and means for drawing the cable close between the welt and the upper.

4. In a support for the welt of a shoe, the combination of a yoke, levers of the first class pivotally mounted on each side of the yoke, each of said levers having a long arm extending along the shoe and a short arm extending in the direction opposite thereto from the pivot, said short arms slightly diverging from each other, a block placed between said short arms, means for pressing said block forward toward the pivot for the purpose of spreading the short arms of the levers and drawing together the ends of the long arms of the levers, extensions on the forward ends of said arms and substantially parallel thereto, said extensions being adapted to engage between the

welt and the upper of the shoe for the purpose of supporting the welt from the upper.

5. In a support for the welt of a shoe, the combination of a yoke, levers of the first class pivotally mounted on each side of the yoke, each of said levers having a long arm extending along the shoe and a short arm extending in the direction opposite thereto from the pivot, said short arms slightly diverging from each other, a block placed between said short arms, means for pressing said block forward toward the pivot for the purpose of spreading the short arms of the levers and drawing together the ends of the long arms of the levers, extensions on the forward ends of said arms and substantially parallel thereto, said extensions being adapted to engage between the welt and the upper of the shoe for the purpose of supporting the welt from the upper, a cable fastened to one of said extensions, said cable passing around the toe of the shoe and being adapted to engage between the upper and welt on the outside of the shoe, a shaft mounted on said yoke to which the free end of the cable is connected, said shaft being capable of being turned for the purpose of drawing the cable tight around the toe of the shoe, means for locking the shaft in position to keep the cable tightly drawn.

6. In a support for the welt of a shoe, the combination of a yoke, levers of the first class pivotally mounted on each side of the yoke, each of said levers having a long arm extending along the shoe and a short arm extending in the direction opposite thereto from the pivot, said short arms slightly diverging from each other, a block placed between said short arms, means for pressing said block forward toward the pivot for the purpose of spreading the short arms of the levers and drawing together the ends of the long arms of the levers, extensions on the forward ends of said arms and substantially parallel thereto, said extensions being adapted to engage between the welt and the upper of the shoe for the purpose of supporting the welt from the upper, a cable fastened to one of said extensions, said cable passing around the toe of the shoe and being adapted to engage between the upper and the welt on the outside of the shoe, and means for drawing said cable tight, said means and cable tending to draw the extensions forward along the diverging sides of the sole by which they are held back against the draft on the cable.

7. In a welt support the combination of means for supporting the welt of the shoe from the outside of the shoe, said means comprising a yoke located at the heel of the shoe, arms pivoted to said yoke, said arms extending forward on either side of the shoe and engaging between the welt and the upper on the outside of the shoe, and means moving towards the heel of the shoe and making sliding engagement with said arms for drawing said arms inwardly between the welt and the upper.

8. In a welt support the combination of means for supporting the welt of the shoe from the outside of the shoe, said means comprising a yoke, arms pivoted to said yoke on each side thereof and extending forward and back therefrom, a stud attached to said yoke between the rearwardly extending portion of the arms, a wing nut mounted on said stud between the rearwardly extending portion of the arms, said arms extending forward on either side of the shoe, and means connecting the forward ends of said arms, said arms and said means engaging between the welt and the upper on the outside of the shoe said

arms being drawn together into place between the welt and upper of the shoe by the turning of the wing nut to spread the rearwardly extending portion of the arms.

9. In a welt support the combination of means for supporting the welt of the shoe from the outside of the shoe, said means comprising a yoke, arms pivoted to said yoke on each side thereof and extending forward and back therefrom, a stud attached to said yoke between the rearwardly extending portions of the arms, and a wing nut mounted on said stud between the rearwardly extending portions of the arms, a block engaging the rearwardly extending portions of the arms, said arms extending forward on either side of the shoe, said arms being drawn together into place between the welt and upper of the shoe by the turning of the wing nut which pushes the block forwardly against the rearwardly extending portion of the arms to spread them.

10. In a support for the welt of a shoe, the combination of a yoke placed back of the heel of a shoe, an arm pivotally mounted on each side of said yoke, extensions on the forward ends of said arms, said extensions being adapted to engage between the welt and the upper of the shoe for the purpose of supporting the welt from the upper, and means located back of the heel of the shoe, said means including a block sliding toward the heel and making sliding engagement with said arms and operating to draw said arms and extensions toward each other from opposite sides of the shoe.

11. In a support for the welt of a shoe, the combination of extensions adapted to engage between the welt and the upper of the shoe on the outside of the sides of the shoe for the purpose

of supporting the welt from the upper forward of the heel, and means extending rearwardly from the heel of the shoe for drawing said extensions toward each other from opposite sides of the shoe, 5 said means including a block sliding toward the heel and making sliding engagement with said arms and operating to draw the extensions toward each other.

12. In a support for the welt of a shoe, the combination of swinging arms having extensions on the forward ends thereof adapted to engage between the welt and the upper of the shoe on the outside of the sides of the shoe for the purpose of supporting the welt from the upper forward of the heel, and means extending rearwardly from the heel of the shoe comprising a yoke located back of the heel, said arms being pivotally mounted on said yoke and extending both forward and back thereof, a block supported from said yoke capable of moving toward the heel and making sliding engagement with said arms back of the yoke for the purpose of drawing said extensions toward the sole of the shoe from opposite sides of the shoe.

13. In a support for the welt of a shoe, the combination of means adapted to engage between the welt and the upper of the shoe from the outside of the shoe on the sides of the shoe, said means engaging between the reentrant part of the half sole and the upper of the shoe, means for pressing said engaging means inwardly from opposite sides of the shoe, and means bearing on the toe of the shoe and engaging between the welt and the upper of the shoe for drawing said 30 engaging means forward into better engagement between the sole and the upper of the shoe.

35

JOSEPH AMICO.
